N. Y., a corporation of New York

Application December 9, 1937, Serial No. 178,895

5 Claims. (Cl. 122—7)

This invention relates to boilers and more particularly waste heat boilers for extraction of heat from hot gases formed in industrial processes.

5 It is an object of the invention to provide a waste heat boiler for the efficient extraction of heat from corrosive, dust laden hot gases, in which hot gases sweep at relatively high velocity over heat transfer surfaces substantially parallel 10 to the direction of flow of the gases, thereby minimizing collection on the surfaces of dust layers preventing efficient and rapid transfer of heat from the gases to the boiler.

It is a further object of the invention to provide 15 a waste heat boiler for the efficient extraction of heat from corrosive, dust laden gases so constructed and designed that in operation a minimum of corrosion of the boiler surfaces takes place.

20 It is a further object of the invention to provide a boiler which requires a minimum of floor space, is of rugged construction and economical to maintain, and which is not subject to failure due to unequal expansion of the boiler parts. 25 Other objects and advantages will appear hereinafter.

In accordance with the invention, I have provided a waste heat boiler of the liquid tube type involving a refractory lined shell surrounding a 30 passageway for flow therethrough of hot, corrosive, dust laden gases, e. g., sulfur dioxide containing gases produced by the suspension roasting in a shaft furnace of finely divided sulfides, such as iron pyrites, pyrrhotite, flotation 35 concentrates, etc., and equipped in the neighborhood of its opposite ends with liquid drums surrounding the passageway and an expansion joint located between the drums. The drums are connected by tubes located within the passageway and providing heat transfer surfaces for the extraction of heat from the gases, the major 40 portions of the tubes extending substantially parallel to the longitudinal axis of the shell, i. e. parallel to the direction of flow of gases through the passageway, and the opposite ends of the tubes being bent toward the shell and communicating with the liquid drums. The connections between the tubes and the drums thus occurs outside the main flow of gases through the passageway. A steam drum is connected to the 45 liquid drums by upcomers and downcomers.

This construction and location of the tubes and the expansion joint compensate for unequal expansion and contraction of the waste heat 50 boiler parts, preventing injurious strains be-

tween the tubes and shell and consequent failure of the boiler parts. The refractory lining and the tubes restrict the path of flow of the hot, dusty, corrosive gases so that the gases sweep at relatively high velocity over the tubes and minimize collection on the tube surfaces of 5 dust layers which would interfere with efficient transfer of heat from the gases to the liquid in the tubes. The lining also protects the connections between the tubes and liquid drums, the 10 parts of the boiler most subject to corrosion, from the direct flow of the hot corrosive gases, thus diminishing the tendency of the connections to corrode.

In the accompanying drawing, where there is 15 shown for purposes of exemplification a preferred embodiment of the invention,

Fig. 1 is a side elevation depicting somewhat 20 diagrammatically the boiler of the invention and apparatus in connection with which it may be employed.

Fig. 2 is a vertical sectional view through the 25 boiler, parts being shown in elevation, and

Fig. 3 is a partial sectional view along line 3—3 30 of Fig. 2.

In the drawing, 1 designates apparatus for producing hot, corrosive, dust laden gases, which may be, for example, a shaft furnace for roasting finely divided sulfides, e. g., iron pyrites, copper pyrites, pyrrhotite, zinc blend and flotation concentrates of the same, while suspended in an oxidizing gas, for the production of sulfur dioxide for use in the manufacture of sulfuric acid, the paper making industry or other purposes. The hot, corrosive, dust laden, sulfur dioxide containing gases produced in shaft furnace 1 may be passed through pipe 2 downwardly through the waste heat boiler of this invention designated generally by reference character 3 where the gases are cooled and steam is generated and then passed through conduit 4 to dust collector 5 or other apparatus.

Referring more particularly to Figs. 2 and 3, the boiler 3 involves a hollow vertical boiler shell 5 surrounding gas passageway 7 and equipped in 45 the neighborhood of its upper and lower ends with annular water drums 9 and 10 respectively, which may be referred to collectively as a liquid chamber. The shell is provided intermediate the drums 9 and 10 with an expansion joint 11. 50 Drums 9 and 10 communicate with each other by means of a series of water tubes 12, the major portions of which lie within the passageway 7 parallel to the direction of flow of gases therethrough, i. e. parallel to the longitudinal axis of 55

shell 5. The upper and lower ends of the tubes are bent toward the boiler shell and are welded or connected in other suitable manner thereto at 13. The water tubes permit flow of water between the drums 9 and 10 and constitute the heat transfer surfaces through which the heat of the gases flowing through the boiler is imparted to the water in the boiler. The bent construction of the water tubes and the expansion joint 11 compensate for unequal expansion and contraction of the tubes and shell and prevent injurious strains which would damage the boiler, e. g. break the connections between the tubes and the shell, with consequent failure of the boiler.

The portions of the interior of the boiler shell adjacent the point of entry of the hot gases and between the water drums 9 and 10 are lined with refractory material 15. This refractory lining forms recesses in the passageway 7 within which are located connections 13 and confines the direct path of flow of the hot, dusty, corrosive gases so that the connections lie without the direct path of gas flow. It will be appreciated that the connections 13 between tubes 12 and drums 9, 10, if subjected to the direct flow of corrosive gases such as sulfur dioxide containing gases, would deteriorate more rapidly due to corrosion than the tube surfaces. The refractory lining not only protects the interior of the boiler shell against corrosion by the gases, but owing to the location of the connections 13 within recesses formed by the lining, protects these connections from the direct flow of the gases thereby minimizing corrosion of the connections.

Refractory lining 15 and tubes 12 restrict the portion of passageway 7 in which the parallel portions of the tubes are located so that the hot gases sweep over these portions of the tubes at a higher velocity than through the remainder of the passageway. The high velocity of the gases and the parallel relation of the tubes to the direction of flow of the gases minimizes collection on the heat transfer surfaces of the tubes of dust layers which would impede transfer of heat from the hot gases to the liquid in the boiler and impair the efficiency of the boiler.

The boiler shell may be provided with hand holes 17 to permit access to the interior of the drums 9, 10 for purposes such as cleaning tubes 12. The exterior surface of the shell is covered with heat insulation 21. Valved outlets 19, 20 may also be provided for draining the drums and removing sediment therefrom.

Steam drum 22 is connected to water drum 10 by downcomers 24 and to water drum 9 by up-comers 26. The steam drum, upcomers, down-comers and tubes 12 provide a circuit for flow of water through the steam drum, water drums and tubes. Reference numeral 30 designates a connection between the top of water drum 9 and the steam drum to prevent steam from accumulating in the upper portion of water drum 9 and reference numeral 32 designates a water gauge on the steam drum. The steam drum is equipped with a steam outlet 34.

The lower end of the boiler shell forms dust collecting chamber 38 into which dust settles from the gases passing through the boiler to outlet 40. Reference numeral 41 designates a closure for the dust collecting chamber which may be opened periodically for removal of dust.

The cooled gases passing from the boiler through outlet 40 may be conducted to a dust collector 5 for removal of the remainder of the

dust and thereafter utilized for any desired purpose, e. g. sulfur dioxide containing gases may be employed in the manufacture of sulfuric acid or paper. Due to the reduction of the temperature of the gases in the boiler below that at which sulfur dioxide corrodes ordinary sheet iron or steel, with consequent reduction of the volume of the gases, the dust collector 5 may be of relatively inexpensive metal construction and small size as compared with the large, refractory dust chambers employed where the sulfur dioxide containing gases are passed directly from the shaft furnace into the dust collecting chamber.

Accordingly, it will be seen the boiler of this invention is economical to maintain and is not subject to failure due to unequal expansion of the boiler parts. The portions of the boiler most subject to deterioration by the corrosive action of gases, such as hot sulfur dioxide containing gases from a shaft furnace, are protected from the direct flow of the gases, thereby minimizing corrosion of the boiler parts. The tubes forming the heat transfer surfaces of the boiler are parallel to the flow of gases and the gas passage in which the tubes are located is restricted so the gases flow thereover at a higher velocity than through the remainder of the boiler, thereby minimizing collection of dust on the tubes and promoting continuously efficient extraction of heat from the gases.

Since certain changes may be made in the above construction without departing from the scope of the invention, e. g. the hot gases may be passed upwardly instead of downwardly through the boiler, it is intended the above description shall be interpreted as illustrative and not in a limiting sense.

What is claimed is:

1. A waste heat boiler comprising in combination a boiler shell providing a passage for flow of hot gases therethrough and spaced liquid chambers, a plurality of tubes within said passageway, portions of said tubes intermediate the ends thereof being substantially parallel to the direction of gas flow through said passageway, the end portions of said tubes being bent outwardly and communicating with said liquid chambers, a refractory lining covering the portion of said shell between said chambers but not the portions of said chambers with which said tubes are connected so that hot gases passing through said shell contact said chambers and the entire exterior surfaces of said tubes, said lining restricting the portion of said passageway within which the parallel portions of said tubes are located whereby said restricted portion is of smaller cross sectional area than the unlined portions of said shell and hot gases pass over the parallel portions of said tubes at greater velocity than through the unlined portions of said boiler.

2. A waste heat boiler for extracting heat from hot dusty gases from industrial processes comprising in combination an upright boiler shell of substantially uniform cross sectional area providing a passageway for flow of hot gases therethrough in one direction only and spaced liquid drums surrounding said passageway, a plurality of tubes having portions intermediate the ends thereof extending substantially parallel to the direction of gas flow through said passageway, the end portions of said tubes being bent outwardly and connected with said liquid drums, the parallel portions of said tubes being spaced from each other and from said shell, a

refractory lining covering the portion of the interior of said shell between said drums and the upper portion of said shell, said lining leaving a substantial portion of said drums connected to said tubes uncovered whereby hot gases passing through said boiler contact said drums and the entire exterior surfaces of said tubes, said refractory lining restricting the portion of said passageway in which the hot gases contact the parallel portions of said tubes so that the gases sweep over the parallel portions of the tubes at greater velocity than through the unlined portions of the shell, said lining protecting the connections between said tubes and said liquid drums.

3. A waste heat boiler for extracting heat from hot, dusty, corrosive gases from industrial processes comprising in combination a vertical boiler shell of substantially uniform cross sectional area providing a top inlet, a bottom side outlet and a passageway for flow of hot gases only in the downward direction therethrough, spaced water drums surrounding said passageway, a dust chamber located at the lower end of said shell, a plurality of tubes within said passageway, portions of said tubes intermediate the ends thereof being substantially parallel to the direction of gas flow through said passageway, the end portions of said tubes being bent outwardly and communicating with said water drums, a refractory lining covering the portion of said shell between said water drums whereby the portion of said passageway in which the parallel portions of said tubes are located is of smaller cross sectional area than the portions of the passageway above and below said lining so that hot gases flow over the parallel portions of said tubes at greater velocity than through the portions of said shell above and below said lining and deposition of dust from said gases onto said tubes is minimized, said dust chamber catching dust settling from said gases owing to the reduction of velocity and change of direction thereof in the lower portion of said boiler shell, a steam drum and upcomers and downcomers located exteriorly of said shell connecting said steam drum to said water drums.

4. A waste heat boiler for extracting heat from hot dusty gases from industrial processes comprising in combination a hollow boiler shell providing a passageway for flow of hot gases in only one direction therethrough, drums surrounding said shell at locations spaced longitudinally thereof and cooperating with the shell to form water spaces, a plurality of spaced water tubes within said passageway, the intermediate major portions of said tubes being substantially parallel to the direction of the gas flow through said passageway, the end portions of said tubes being bent outwardly and communicating through said shell with said water

spaces, a refractory lining of substantial thickness covering the portion of the interior of said shell in which the parallel portions of said tubes are located whereby the portion of said passageway in which hot gases flow over the parallel portions of said tubes is of smaller cross sectional area than the portions of the passageway at the ends of said lining so that the hot gases flow over the entire surfaces of the parallel portions of said tubes at greater velocity than over the bent portions of said tubes and deposition of dust from said gases onto said tubes is inhibited, said shell having an expansion joint extending circumferentially therearound at a location between said drums, said expansion joint and the bent construction of said tubes compensating for unequal expansion of said shell and tubes owing to temperature changes.

5. A waste heat boiler for extracting heat from hot, dusty, corrosive gases from industrial processes comprising in combination a vertical cylindrical boiler shell of substantially uniform cross sectional area providing a top inlet, a bottom side outlet and a passageway for flow of hot gases only in the downward direction therethrough, cylindrical drums surrounding said shell and forming therewith water spaces extending circumferentially around the shell, a plurality of spaced water tubes within said passageway, the major portions of said tubes intermediate the ends thereof being substantially parallel to the direction of gas flow through said passageway, the end portions of said tubes being bent outwardly and communicating through said shell with said water spaces, a refractory lining covering the portion of said shell between said water spaces whereby the portion of said passageway in which the parallel portions of said tubes are located is of smaller cross sectional area than the portions of the passageway above and below said lining so that the hot gases flow over the parallel portions of said tubes at greater velocity than through the portions of said shell above and below said lining and deposition of dust from said gases onto said tubes is inhibited, a refractory lining covering the upper end portion of the interior of said shell, said linings providing a recess within which the connections between the upper ends of said tubes and said shell are located thereby protecting said connections from the direct flow of the hot corrosive gases without preventing heat exchange between the gases and liquid in said drums through the shell, a dust chamber in the lower portion of the shell, an expansion joint extending circumferentially around said shell intermediate said drums, the bent ends of said tubes and said expansion joint compensating for unequal expansion and contraction of said boiler longitudinally of said shell, a steam drum, and upcomers and downcomers located exteriorly of said shell connecting said steam drum to said water spaces.

ROBERT BRUEN FERGUSON.
